(57) **CLAIM**

The ornamental design for a hook keeper, as shown and described.

DESCRIPTION

FIG. 1 is a perspective view of the hook keeper of the present design;

FIG. 2 is a side view of the hook keeper of FIG. 1;

FIG. 3 is another side view of the hook keeper of FIG. 1, with the hook attachment ring open;

FIG. 4 is a partial sectional side view of the hook keeper of FIG. 1 taken from lines 4-4 and 5-5 in FIG. 3;

FIG. 5 is a partial sectional side view of the hook keeper of FIG. 1, taken from line 5-5 in FIG. 3, shown with both ends engaged on a hook; and,

FIG. 6 is a perspective view of the hook keeper of FIG. 1, shown with the hook attachment ring engaged on a hook. The broken lines represent environment that forms no part of the claim.
